UNITED STATES PATENT OFFICE.

ISAAC T. WOODUFF, OF PORTLAND, OREGON.

AUTOMATIC STOKING DEVICE.

Application filed August 31, 1927. Serial No. 216,623.

My present invention relates to my United States Patent No. 1,618,501 issued February 22, 1927, upon an automatic feeder of mill waste fuel for domestic heating.

The primary object of my present invention is for feeding mill waste fuel. Another object of my present invention, consists in providing simple and automatic means for the feeding of comminuted fuel continuously and automatically to a furnace in which the same is being used.

A further object of my invention consists in providing a feeding hopper, means being provided for the shifting of the hopper into alternate directions and imparting a jarring motion during each cycle of operation; automatic means being also provided for the changing of the slope of the feeding stream from the base of the hopper on to the feeding conveyor for transferring the material into the furnace.

Means is also provided for regulating the volume of the fuel stream from the hopper over a sloping surface to a conveyor and distributing element associated therewith, and for predetermining the rate of deposit into the combustion chamber.

Means is also provided for predetermining the speed of travel of the conveyor.

Means is also provided for shifting the hopper into and out of association with the furnace and means being provided for the removal of the conveyor from the furnace firebox for adjustment and repair.

Additional objects of my invention are an automatic stoker that may be easily made accessible for repair and simple means for its removal or adjustment with respect to the firebox.

An additional object of my invention is in providing an automatic stoker for comminuted fuels, that will operate continuously without attention other than the filling of the hopper.

With these and incidental objects in view, the invention consists in certain novel features of construction and combination of parts, the essential elements of which are set forth in the appended claims, and a preferred form of embodiment of which is hereinafter shown with reference to the drawings which

accompany and form a part of this specification.

In the drawings:

Fig. 1 is a front elevation of that portion of my device that is disposed exteriorly of the firebox.

Fig. 2 is a sectional, side elevation, of the mechanism illustrated in Fig. 1 and also of the firebox, the same being taken on line 2—2 of Fig. 1, looking in the direction indicated.

Fig. 3 is a side elevation of that portion of the mechanism disposed exteriorly of the firebox, and is taken on line 3—3 of Fig. 1, looking in the direction indicated.

Fig. 4 is a sectional view, taken on line 4—4 of Fig. 2, looking in the direction indicated.

Fig. 5 is a top, plan view, of the firebox mechanism, and is taken on line 5—5 of Fig. 2, looking in the direction indicated.

Fig. 6 is a fragmentary, sectional view, taken on line 6—6 of Fig. 2, looking in the direction indicated, the same being made to illustrate a portion of the sloping feeding surface adapted to convey, and distribute, the fuel stream from the hopper outlet to the conveyor table.

Fig. 7 is an end elevation, partially in section of the exterior of the firebox door of the furnace.

Fig. 8 is a fragmentary, side elevation, taken on line 8—8 of Fig. 1, of the feeding mechanism, same being made to illustrate the automatic take-up for predetermining the rate of travel of the conveyor disposed longitudinally of the firebox.

Fig. 9 is a fragmentary, top, plan view, of the feeding pawl and ratchet, the same being taken on line 9—9 of Fig. 8, looking in the direction indicated.

Fig. 10 is a fragmentary, top, plan view, of the feeding mechanism, the same being taken on line 10—10 of Fig. 8, looking in the direction indicated.

Fig. 11 is a fragmentary, end view, of the mechanism illustrated in Fig. 8, the same being taken on line 11—11 of Fig. 8, looking in the direction indicated.

Like reference characters refer to like parts throughout the several views.

My invention in the illustrative form of

embodiment disclosed herein is intended for application in fireboxes wherein comminuted fuels and especially sawmill waste fuels are used. In the form as herein outlined, the device meets all of the requirements for the purposes intended. However, certain features of the device are admirably adapted for use in other forms of automatic stokers. The accompanying drawings show the invention 10 in preferred form adapted to the stoking of comminuted and sawmill waste fuels. It is understood that it is not intended to limit the invention to such use, as it is well adapted, in modified forms, to the stoking of other kinds of fuel.

Described in general terms the stoker consists of a feeding hopper 1, having supporting elements 2 and 3, disposed at opposite sides and secured thereto by suitable fastening means. Trunnion shafts 4 and 5 extend outwardly therefrom and form journals for supporting the hopper and about which the same may be made to partially rotate in its use. Brackets 6 and 7, support the shafts 20 4 and 5 and form bearings in which the shafts rock. A fuel conduit 8 supports the brackets and connects with the bottom of the hopper 1 and through which the fuel is fed into the firebox. The fuel conduit 8 is secured directly to the firebox 9. The fuel conduit 8 may be incorporated in a fire door 10 supported upon hinges 11, which may be opened to give access to the firebox, without the necessity of dismantling of the hopper 25 and the associated elements. Disposed adjacent the lower edge of the hopper and on the inner edge of the same is a comb-like surface composed of teeth 12, the object of which is to break up the fuel stream as the same moves therepast. A gate 13 may be utilized to check the flow of fuel from the hopper into the firebox, the same being adapted for manual manipulation and adjustment. Corrugated strips 14 are secured to one side of the hopper and extend forwardly therefrom and are provided with uneven and corrugated surfaces, over which the fuel stream is made to pass. The strips 14 are preferably made of flexible material that will permit of their being raised or lowered or otherwise adjusted. The adjustment is accomplished through the raising and lowering of the adjustment plate 15 disposed on the underside of the strips 14. An arm 16 as illustrated in Fig. 3, extends through the side wall of the fuel conduit 8 and has a lever arm 17 secured thereto which coacts with a ratchet quadrant 18 to permit of the adjustment of the plate 15 to regulate the pitch or slope of the strips 14 which ride thereon.

I have observed that there is an ever present tendency of the comminuted fuels to arch over and prevent the further feeding of the fuel through a restricted opening from a container. To prevent this, and to facilitate a

regular and even feeding of the fuel from the hopper into the firebox, I have provided means for an intermittent rocking movement of the hopper and to violently shock the same during each cycle of the movement. 70 This is accomplished through the action of pitman rod 19 secured to the wrist pin 20 of the sprocket disc 21. The pitman rod 19 is pivotally connected to the lever 22, which in turn is attached to the shaft 4, and the shaft 75 4 is rocked through the raising and lowering of the lever 22, brought about by the reciprocation of the pitman, a rocking action is imparted to the hopper 1. Adjusting holes are placed in the adjusting lever that permit 80 of the locating of the pitman rod to the position necessary for the kind and character of the fuel being used. The hopper 1 is mounted upon the supporting shafts in a manner allowing it to be easily tilted, in either direction, without the necessity of the expenditure of any considerable energy. As the hopper is tilted, over center, in either direction gravity has a tendency to over rotate the same, and the absorbing of this tendency, 85 to the over rotation of the hopper about its supporting shafts, imparts a shock to the hopper. This shock of the hopper has a tendency to prevent the arching or packing of the fuel. To increase the shock the hopper 90 may be made to strike a resistance beam disposed across and adjacent the lower end of the path of travel of the hopper. The rocking of the hopper imparts a reciprocal action to the corrugated strips 14 and since 95 the corrugated strips 14 are stepped in its longitudinal surface contour, the same causes a downward feeding action to the fuel stream passing thereacross.

The sprocket disc 21 is mounted upon the shaft 22^A journaled within bearings 24 and 25 which are supported upon the rear wall of the fuel conduit 8. A toothed ratchet wheel 26 is secured to the shaft 22^A, as illustrated in Fig. 8. The rotation of the shaft 105 22^A is accomplished through the connecting rod 27, secured to the arm 28 carrying the feeding pawl 29. The feeding pawl 29 is made to engage the teeth of the toothed wheel. Retrograde movement is prevented 110 by the dog 30 engaging the teeth of the ratchet wheel and to maintain the same in advanced position. Regulation of the speed of rotation of the ratchet wheel may be accomplished through the adjustment of the stroke being imparted to the connecting rod 27. Disposed at the lower end of the connecting rod 27 is a guide block 31, having an elongated guide slot 32, in which the wrist pin 33 secured to the driving disc is made to 115 engage. The effective length of the slot 32 may be regulated by the adjusting screw 34 that is threaded within the lower end of the guide block. The inner end of the threaded screw 34 serves as a stop to the travel of the 120

wrist pin relative to the slot length. Thus a long length of slot will provide increased speed of rotation and a short length of slot will provide decreased speed of rotation of the ratchet wheel. A prime mover 35 drives the worm wheel 36 mounted on shaft 37. The disc 38 is also secured to shaft 37 and the wrist pin 33 is secured to the disc 38. A bracket housing 39 supports the shaft 37, disc 38, and worm wheel 36.

Running longitudinally of the firebox is a conveyor which receives at one end thereof the fuel stream being discharged within the firebox from the fuel conduits 8, and the fuel stream deposited thereupon is carried into the firebox where it is distributed over a combustion bed.

The conveyor is best illustrated in Fig. 2 and Fig. 5 wherein longitudinal side frames 40 and 41 run longitudinally of the firebox. Two longitudinal supporting beams 44 and 45 also run longitudinally of the fire box and act as supporting and guide rails upon which the wheels 42 and 43 are made to pass. The wheels 42 and 43 are disposed upon the inner ends of the side frame members and act as supporting wheels for the inner end of the conveyor and at the same time act as supporting wheels when it is found desirable to remove the conveyor wholly, or partially, from the firebox. Mounted upon the shaft 46 upon which the supporting wheels are disposed, are sprocket wheels 47 and 48 about which the conveyor chains 49 of the conveyor pass. The chains 49 are connected and have extending between them cross bars 50 which act as a drag for conveying the fuel along the bottom 51 of the conveyor.

The conveyor extends outwardly from the front of the firebox and its outer end is carried upon a bracket 52. The bracket 52 has disposed upon its lower end a trunnion wheel 53. When it is desired to remove the conveyor from the furnace, the driving chain 54 may be removed from the sprockets and the conveyor as a whole may be then removed from the furnace and from the firebox, by the front end of the conveyor being rolled out upon the trunnion wheels 53 and by the rear 50 of the same being carried upon the supporting wheels 42 and 43 rolling on the rails 44 and 45. For the tightening of the conveyor chain and to compensate for expansion and contraction, I have placed on the outer ends 55 of the conveyor frame a take up head composed of springs 55 disposed between the yoke 56 and the end 57 of the conveyor frame. A plate 58 is placed between the outer ends of the springs 55 and the inner side of the yoke. Threaded adjustment elements 59 permit of an adjustment being made and the springs provide for automatically taking care of the expansion and contraction caused by the heat, and for maintaining a working stress in the 60 conveyor chain.

A noncombustible base plate 60 is disposed longitudinally of the conveyor and longitudinal slots 61 and 62 are disposed within the base 60. The slots 61 and 62 increase in width rearward as illustrated in Fig. 5; the object of which is to permit of a uniform distribution of the fuel deposited therethrough over the full length of the combustion area. To prevent combustion within the conveyor and to protect the conveyor chain from becoming clogged, I have placed shields 63 and 64 at either side of the conveyor, the same running substantially the full length of the conveyor frame.

To facilitate combustion, I have placed at the bottom of the firebox a number of air grates 65 and 66 that have outwardly sloping side walls. Holes 67 are disposed through the bodies of the grates to facilitate the passage of air for combustion therethrough.

While the form of mechanism shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of a fuel hopper, means for supporting the fuel hopper, means for tilting the fuel hopper in alternate directions, a fuel conduit disposed below and communicating with the fuel hopper, and corrugated strips secured to the hopper and extending downwardly through the fuel conduit.

2. In a device of the class described, the combination of a fuel hopper having downwardly and inwardly sloping side walls with a passageway disposed through its lower end, supports disposed at opposite sides of the hopper, a fuel conduit communicating with the lower end of the hopper and in registerable alignment with the outlet end of the hopper, corrugated strips each having a stepped surface contour and means for moving the hopper and the corrugated strips first in one direction and then in the opposite direction.

3. In a device of the class described, the combination of a fuel hopper, outwardly extending journal shafts disposed upon opposite sides of the hopper, journal bearings for said journal shafts, an outlet disposed at the lower end of the hopper, a fuel conduit disposed below the lower end of the hopper adapted for conducting fuel from the hopper into the firebox, corrugated strips extending from the lower end of the hopper through the fuel conduit and into the firebox and means for imparting an intermittent movement to the hopper and the corrugated strips.

4. In a device of the class described, the combination of a fuel conduit, a fuel hopper

disposed above the fuel conduit and supported thereby and means for imparting a rocking motion to the hopper and a horizontal movement to the fuel conduit.

5. In a device of the class described, the combination of a fuel conduit secured to the fire door of a furnace and hinged rela-

tive to the firebox as the door is manipulated, a fuel hopper superposed relative to the fuel conduit and indirectly supported thereby, and means for imparting a rocking motion to the hopper.

ISAAC T. WOODRUFF.
